Michael Givney, New York City, N.Y.
Letters Patent No 184 dated June 13, 1848

The schedule referred to in these letters Patent and
making part of the same.

To all whom it may concern:

Be it known that I,
Michael Givney, of the City, County and State of
New York, have invented or produced a new and im-
proved shape and embellishments for the handles of
spoons, forks, saddles and other articles of table use to
which they will apply, and I do hereby declare
that the following is a full and exact description

of the same, reference being had to the annexed drawings which make a part of this specification.

My invention is confined to the form of the head and the embellishments, (which are in the Louis 14th style of art) which are embossed thereon as seen in Figure 1st from A to B and from C to D. The form of the head is elliptical and bounded by two principal scrolls curving upwards and inwards, and met by two smaller scrolls curving downwards. The lower termination of the ornaments for the back of the article are seen from C to D which are two scrolls curving outward supporting two scrolls curving inward. The termination of the ornaments on the front is seen in figure 2nd, which are small leafy scrolls.

Claim

What I claim and desire to secure by Letters Patent is the peculiar form of the head as herein set forth for the handles of spoons, forks, paddles and other articles of table use, together with the embellishments herein described, to be embossed upon the handles back and front, of the above named articles.
